UNITED STATES PATENT OFFICE.

JAMES L. BOATNER, OF WHITAKER, MISSISSIPPI, ASSIGNOR TO HIMSELF AND RICHARD WHITAKER, OF SAME PLACE.

DESIGN FOR A CUTTER.

SPECIFICATION forming part of Design No. 21,007, dated August 25, 1891.

Application filed June 30, 1891. Serial No. 398,079. Term of patent 14 years.

To all whom it may concern:

Be it known that I, JAMES L. BOATNER, a citizen of the United States, residing at Whitaker, in the county of Wilkinson and State of Mississippi, have invented and produced a new and original Design for Cutters, of which the following is a specification.

Reference is to be had to the accompanying drawings, forming a part of this specification, 10 in which—

Figure 1 is a front elevation of a cutter embodying my new design, and Fig. 2 a plan view thereof.

The design consists in the peculiar configuration of the cutter.

The letter A indicates the blade or cutter proper, and B the shank or tang thereof.

The lines a^1 of the blade A are curved longitudinally and forwardly and merge into each other at the forward end a' . The inner 20 end a^2 of the blade is diagonal, from which diagonal end the lines of the shank B depart, and said shank is disposed approximately at a right angle to the longitudinal axis of the blade and at an angle to the transverse axis 25 of the blade.

I claim—

The design for a cutter, as shown and described.

JAMES L. BOATNER.
